INSERT-PLUG LOCK

Otis A. Causey, Crows Landing, Calif.

Application November 11, 1930, Serial No. 494,909
Renewed February 20, 1933

1 Claim. (Cl. 70—124)

This invention relates to insert plugs for the filling or drain openings of the drums, tanks and other containers of various kinds, and particularly to the plugs of drums in which gasoline and other fuels, lubricating oil, and like products are sold by the oil companies to their customers, especially on ranches and the like.

The ordinary plugs can be easily removed upon the application of a wrench, and owing to the exposed locations in which said drums are commonly placed the theft of their contents is somewhat common.

The principal object of my invention is to avoid the unauthorized removal of the plugs and the consequent theft of the contents of the drums by means of a plug of this general character which, while arranged so as to be inserted in or removed from place as easily as the plugs now employed, is provided with a lock structure which will positively prevent removal of the plug unless the proper key is first used to disengage the locking bolt.

A further object is to provide a double lock structure of such a nature that the primary key-controlled lock may be small and relatively delicate, as the somewhat intricate but efficient cylinder and pin type locks usually are; while the secondary lock which is controlled by the key lock may be as stout as may be needed to withstand the strains imposed thereon with any attempt to unscrew the plug, while the secondary lock bolt is in its operative position.

A further object of the invention is to produce a simple and inexpensive device, and yet one which will be exceedingly effective for the purpose for which it is designed.

These objects I accomplish by means of such structure and relative arrangement of parts as will fully appear by a perusal of the following specification and claim.

In the drawing similar characters of reference indicate corresponding parts in the several views:

Fig. 1 is a sectional elevation of my improved plug as in position in the drum socket and in its locked position.

Fig. 2 is a similar view with the secondary lock retracted or disengaged.

Fig. 3 is a sectional plan on the line 3—3 of Fig. 1.

Referring now more particularly to the characters of reference on the drawing, the numeral 1 denotes a tank or drum provided with a depressed insert-plug retaining collar which comprises a lower or inner tapped portion 2 and an

upper or outer relatively large cup portion 3 which is secured about its rim to the drum.

The plug comprises a central body portion 4 threaded to engage the tapped portion 2, and extension 5 below the threaded portion, and an upper outwardly projecting flange 6 above said threaded portion, which flange is polygonal sided, so that it may be engaged by a wrench. The plug is provided with a centrally disposed circular bore 7 which extends downwardly into the extension 5 from the upper end of the plug and in which a barrel 8 is turnably fitted. Adjacent but below its upper end the barrel is provided with an integral outwardly projecting collar or flange 9 which seats in the correspondingly enlarged portion of the bore. This collar and consequently the barrel as a whole is held against removal from the bore by a ring 10 which is pressed into the enlarged bore portion about the barrel and above the collar, and is flush with the top of the plug and the barrel. This ring is arranged so as not to interfere with the freedom of turning of the barrel, but owing to the flush arrangement of the barrel ring and plug, it will be obvious that neither the ring nor the barrel can be removed from above with the use of any ordinary tools. Pressed into the barrel from its upper end is the cylinder 11 of a standard lock structure of the multiple pin tumbler type, in which the release or withdrawal of the radial lock bolt 12 is effected by the insertion of the proper key into the cylinder and the consequent rotation of said key. The bolt projects laterally from the cylinder below the collar and through the adjacent sidewall of the barrel, being adapted at its outer end to seat in either one of the diametrically opposed recesses or sockets 13 cut in the plug from the bore of the barrel.

Extending radially of and slidably mounted in the plug extension, below the threaded portion is a lock bolt 14, having an enlarged head 15 on its inner end, and a spring 16 bearing against said head to force the bolt inwardly of the plug or so that its outer end is retracted inwardly of the line of the threads.

The portion of the barrel which lies in the horizontal plane of the bolt 14 is in the form of a cam or eccentric 17 of oval cross-section, as shown in Fig. 3. One side of this cam is flush with the corresponding side of the barrel, but its opposite side is substantially in line with the central axis of the barrel. The bolt is so arranged that when the barrel is turned so that the outer or flush side of the cam bears against the head of the bolt, the latter is projected out-

wardly of the plug some distance or so as to engage the adjacent end of the collar 2 if an attempt is made to unscrew the plug. The primary lock bolt 12 then registers with one of the 5 sockets 13.

To aid in initially locating the cam relative to the bolt 14 when the latter is in its advance position, and before the bolt 12 is allowed to project into its socket, the bolt engaging face of 10 the cam is recessed somewhat as at 18, so as to provide a seat for the correspondingly shaped head of the bolt 14. When the barrel is turned through an arc of 180 degrees from this position, or so that the opposite or offset face of the cam 15 is pressed against the head 15 of the bolt, said bolt will be then completely retracted relative to the threaded portion of the plug and socket so as to offer no interference with the unscrewing of the plug.

20 In operation to unlock the plug, or in other words to retract the bolt 14 so that the plug may be unscrewed the proper key is inserted in the cylinder 11 and turned in the direction necessary to retract the bolt 12 from its socket. A further rotation of the key after said bolt has been thus retracted then turns the lock cylinder and barrel as a unit, reversing the position of the cam. With such reversing the bolt 14 is automatically retracted, since the spring 16 is always 25 acting on said bolt to draw the same inwardly. The plug may then be removed as usual by the application of a wrench.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

An insert plug for a tank-opening collar comprising a hollow body to fit in said collar and having an extension to project inwardly of the collar when the plug is in place, a spring retracted lock bolt mounted in and movable radially of the extension to project under the collar, a barrel turnably mounted in the body and exposed to the top of the same, a cam on the lower end of the barrel disposed in eccentric relation to the axis thereof and arranged to engage the inner end of the bolt and move the same outwardly when the barrel is turned, and lock means for the barrel to maintain the cam in a bolt advancing position, the cam being provided with a depression in its bolt advancing face to removably receive the inner end of the bolt, whereby to yieldingly resist turning of the cam from a bolt advancing position.
